UNITED STATES PATENT OFFICE

2,478,867

ELECTRICAL MUSICAL INSTRUMENT

John M. Hanert, Wilmette, Ill., assignor to Hammond Instrument Company, Chicago, Ill., a corporation of Delaware

Application March 20, 1942, Serial No. 435,499

37 Claims. (Cl. 84—1.24)

1

My invention relates generally to electrical musical instruments and more particularly to a solo instrument of this type.

It is an object of my invention to provide an improved solo type electrical musical instrument in which the intensity envelopes of the tones may be readily controlled.

A further object is to provide an instrument of the foregoing type in which the player, by the extent of depression of the playing keys, may control the intensity envelopes of the tones.

A further object is to provide an improved tone quality modulating effect in the output of an electrical musical instrument, in the nature of a quality vibrato.

A further object is to provide a second touch tone intensity envelope controlling circuit in which the character of the envelopes of the tones may be preselected.

A further object is to provide an electrical musical instrument having pitch determining playing keys, and having a separate group of tone intensity envelope determining keys playable simultaneously with the pitch determining keys.

A further object is to provide an electrical musical instrument having an output system including a non-linear distortion circuit, the output of which comprises predominantly the odd harmonics of the fundamental frequency of the input signal.

A further object is to provide an electrical musical instrument having a plurality of interlocked octave interval oscillators tunable by the playing keys throughout the range of several octaves, and having output circuits which may be employed singly or in combinations to provide octave coupler effects.

A further object is to provide an output circuit for an electrical musical instrument having an electron discharge device provided with a control grid and a second grid, such as a screen grid, in which the amplitude of the signal transmitted by the device is determined by a resistance-capacitance network connected to the second grid in a manner such that the current drawn by said second grid may change its effective potential.

A further object is to provide an improved expression control for electrical musical instruments in which the natural frequency of a tone quality mesh is shifted as the volume is changed.

Other objects will appear from the following description, reference being had to the accompanying drawings in which:

Figures 1, 1a and 1b together constitute a wiring diagram of the complete instrument less the power supply system;

Figure 2 is a modified output and envelope control circuit which may be utilized in place of a portion of the output circuit shown in Fig. 1b, as substituted for that portion of the diagram

2

which is embraced between broken lines *a—a* and *b—b*; and

Figure 3 is a diagrammatic view of one of the playing keys and switches operated thereby.

My invention, considered generally, constitutes an improvement upon the instruments disclosed in my prior Patent No. 2,254,284, in the prior patents to Laurens Hammond Nos. 2,203,569, 2,251,052, 2,253,782, and in the patent to Hammond et al. No. 2,233,258.

Generating system

Referring to Figure 1, the generating system is illustrated as comprising a master oscillator 10 driving a relaxation oscillator 12 of the same frequency. The relaxation oscillator 12 supplies a frequency controlling signal for a cascaded series of controlled oscillators 14, 16, and 18, which are in the form of frequency dividing relaxation oscillators, the constants of which are such as to cause them successively to halve their input controlling frequencies. This generating system may be the same as that shown in the aforesaid Patent No. 2,233,258 except that due to the fact that the oscillators may be tuned by the playing keys through the entire three octave range of the keyboard, two less stages of controlled oscillators are required.

The generating system supplies four output signals in octave relationship, the highest frequency of the soprano signal being derived from the master oscillator 10 through a conductor 20, the next highest or contralto signal being derived from the oscillator 14 through a conductor 21, the third highest or tenor signal being derived from the oscillator 16 through a conductor 22, and the lowest or bass signal being derived from the oscillator 18 through a conductor 23. Each of the signal conductors 20, 21, 22, 23 has a de-coupling resistor R1 connecting it to a manually operable coupling or register determining switch 26 by means of which the desired signals may be impressed upon the grid of a preamplifier tube 28.

The master oscillator 10 is tunable through a range of three octaves plus a semi-tone by playing keys 30 designated additionally by the semi-tone notations of musical notes controlled thereby. Each of the keys 30 successively operates three switches 31, 32, and 33 in the order named. (The key 30 for the highest C note need not be provided with a switch 31.) Condensers C1 connected in series are adapted to be selectively connected by switches 31 to a grounded conductor 34 by operation of the playing keys 30, and thereby determine the resonant frequency of the tuning circuit of the master oscillator 10. A plurality of resistor elements R2 are likewise connected in series and adapted to have their junction points 55 connected to grounded conductor 34 by the key 30.

switches 31. Resistors R2 form part of a voltage dividing network which includes resistors R3, R4 and R5 and determines the grid bias on the controlled oscillators 14, 16 and 18. At intervals in series with the resistors R2 there are provided inductances L1 which suppress sparking upon closure of the switches 31. A variable condenser C6 may be adjusted to compensate for the distributed capacity in this voltage divider network, particularly in the conductor which connects the resistors R3 and R4 to the keyboard resistors R2. Condenser C7 is provided to compensate for the distributed capacity of the conductor which connects the keyboard condensers C1 to the master oscillator 10.

The circuits for tuning the master oscillator 10 by means of the playing keys are essentially the same as those disclosed in the aforesaid Patents Nos. 2,233,258 and 2,254,284, to which reference may be had for a more detailed description.

A vibrato apparatus 36 is connected to the tuning circuit of the master oscillator 10 and is adapted to change the tuning of the master oscillator periodically at approximately 7 C. P. S. between a frequency of 1½% above and 1½% below the nominal oscillator frequency when a wide vibrato is desired, and through a considerably smaller range when a narrow vibrato is desired. This vibrato apparatus may be of the type shown in the patent to Laurens Hammond, No. 2,251,052, and in my co-pending application Serial No. 361,065, filed October 14, 1940, which has matured into Patent No. 2,301,871.

Mute and odd harmonic distortion system

The signals from the oscillators, as determined by the operation of the playing keys 30 and the positions of the register controlling switches 26, are impressed upon the grid of the preamplifier tube 28, which may be of the 7B6 type. The output of this tube 28 is capacity coupled to the input of a mute tube 40 which may be of the 7A7 type and operates as disclosed in my co-pending application Serial No. 361,064, filed October 14, 1940, now Patent No. 2,276,390, issued March 17, 1942. The tube 40 is adapted, when a mute switch 42 is open, to modify the tone quality so as substantially to reduce its harmonic content without emphasizing low frequency transients which may be applied to its input. The output of the mute tube 40 is impressed on a terminal 44. The mute tube 40 is in parallel with an odd harmonic distortion circuit including a triode 46 (7A4 type) and a pentode 48 (7A7 type).

The triode 46 has its grid 49 connected to the plate of the preamplifier tube 28 through a blocking condenser C2, a decoupling resistor R6, and a series grid resistor R7, the junction 50 between the resistors R6 and R7 being connected to ground through a grid resistor R8. It is to be noted that there is no bias on this tube as both the resistor R8 and its cathode 45 are connected to ground. Therefore, when positive pulses are impressed upon the junction 50, the grid 49 will tend to go positive. However, when this grid is positive, it will draw current and thus the resistor R7 will limit this current and distort the wave shape on the positive portion of the signal wave. As a result, the output of the tube 46 will have a flattened wave shape corresponding to the time at which the grid signal is positive. It is to be noted that this flattening will not be perfectly horizontal, but will have some curvature due to the effect of the series grid resistor R7 at various amplitudes of positive signal. This is desirable

musically, since the output wave should not contain a predominance of high order harmonic frequencies. The operation of the triode 46 upon the negative portion of the grid signal will be linear in most cases but for a high amplitude signal may approach cutoff, in which case some harmonic distortion will occur on the negative swing as well as on the positive swing.

The plate 51 of the tube 46 is connected to a terminal +300 v. of the power supply system through a plate load resistor R9 upon closure of a switch 52. The signal on the plate 51 is transmitted to the grid 54 of the pentode 48 through a blocking condenser C3, a decoupling resistor R10, a series grid resistor R11, and a grid resistor R12 connected between ground and the junction 56 of the resistors R10 and R11. The screen 58 of the pentode 48 is adapted to be connected to the terminal +300 v. of the power supply, upon closure of the switch 52, through a voltage dropping resistor R14, and is connected to ground through a condenser C4.

The cathode 60 and suppressor grid 62 of the tube 48 are connected to ground while the plate 64 thereof is connected through a plate load resistor R16 to a terminal +300 v. A pair of condensers C8 and C9 may be connected in parallel with resistor R16 upon closure of switches 66 and 68 respectively. The output of the pentode 48 is connected through a blocking condenser C10 and decoupling resistor R18 to the terminal 44. Condenser C10 and resistor R18 are made current limiting for low frequencies in order to remove undesirable low frequency transients and also to reduce the low frequency response of the system. The attenuation of low frequencies is also for the purpose of preventing overloading of the speaker.

It has previously been shown how the triode 46 is effective to flatten the positive portion of the input wave. Since triode 46 reverses the phase of the signal wave and since the pentode 48 also operates with zero control grid bias, the pentode 48 correspondingly flattens the positive portion of its input wave—which corresponds to the negative portion of the original input wave on the grid of tube 46. It will therefore follow that the output of the pentode 48 will comprise waves having generally vertical sides with smoothly rounded tops and bottoms. Harmonic analysis of a signal wave of this shape shows that the odd harmonics are emphasized at the expense of the even harmonics. By properly adjusting the amplitude of the signal and the circuit constants for this two stage non-linear transmission system, it is easily possible to render the wave of generally square wave shape so that the even harmonics are practically absent. When this is the case, the characteristic tones of stopped organ pipes, clarinets and other stopped pipe instruments may be simulated.

The harmonic content of the wave appearing at the plate 64 of the tube 48 may be further reduced by operation of the switches 66, 68 which function to shunt condensers C8, C9 respectively across the plate load resistor R16. These condensers in shunt with the resistor R16 make up a tone quality mesh which offers greater impedance for low frequencies than for high frequencies, and therefore the tone is made more mellow when either or both of the switches 66 or 68 are closed.

From the foregoing it will be clear that the tubes 46 and 48 and associated circuit elements constitute a simple and effective means for securing distortion with a relatively low amplitude in-

put signal, in a manner to obtain an output signal whose harmonic content differs completely from, and to a considerable extent is independent of, the harmonic content of the input signal.

The screen of the mute tube 40 is adapted to be connected to a +300 v. terminal of the power supply by operation of a switch 70 when the mute tube is to be utilized. To assure proper coordination between the operation of the switches 42, 52 and 70 they are preferably made in the form of three-position switches and are mechanically interconnected. In their uppermost positions, these switches permit the transmission of the signal directly from the preamplifier tube 28 to the terminal 44 through the switch 42. In the intermediate positions of these switches the mute tube is effective to modify the signal, the transmission in this case being from the preamplifier tube 28 through the mute tube 40 to the terminal 44. When these switches are in their lowermost positions, the only transmission path for the signal from the preamplifier tube 28 is through the two stage odd harmonic distorting system including the tubes 46 and 48. Thus, it is possible, depending upon the positions of the switches 42, 52 and 70 to obtain an output wave shape of any one of three different forms, namely, (a) the output signal of the tube 28 without distortion—when the switch 42 is closed; (b) a signal which is of the form described in detail in Laurens Hammond Patent No. 2,126,424 (particularly the description with reference to Figs. 19 and 20 there) in which the amplitudes of the harmonics tend to decrease logarithmically—with switch 42 open and switch 70 closed; and (c) the odd harmonic distortion by the tubes 46 and 48 previously described—with switches 42 and 70 open and switch 52 closed.

The terminal 44 is connected to ground through the primary winding of an interstage transformer T1, which winding is shunted by selectively operable tone control meshes 72, consisting of various combinations of inductance, capacitance and resistance resonating or emphasizing different frequencies, these meshes being selectively rendered operable by opening associated tone control switches 74.

The quality vibrato

Novel and interesting musical effects may be obtained by changing the resonant frequencies of selected meshes 72 at a vibrato or tremolo rate, such change being most effective on the resonant networks such as those illustrated for the first, second, and third voices. The means for accomplishing this result comprises a plurality of condensers C12, each having one terminal thereof adapted to be connected to a junction 76 through a manually operable switch 77 and a condenser C14. The other terminals of condensers C12 are respectively connected to switch contact arms 78 which are adapted to be periodically and sequentially connected to ground by operation of any suitable mechanism, such as a grounded cam 82 rotated at approximately 7 revolutions per second by a motor 84 through a suitable gear train. The motor 84 is connected to a suitable source of current upon closure of a switch 86 which may be closed incidental to the closure of the instrument's main power supply switch (not shown).

A condenser C13 is adapted to be connected effectively in parallel with the condensers C12 upon closure of a switch 88 which is mechanically connected to a switch 90, the latter switch being closed when the switch 88 is open and vice versa.

The switch 90 is connected in a circuit by which the condenser C14 may be shunted.

Assuming the switch 77 to be closed, when in the first instance, the switches 88 and 90 are in the positions shown, that is, the switch 88 being open and the switch 90 closed, both condensers C13 and C14 are ineffective, and the condensers C12, upon successive closure of the switches 78, are effectively connected between the junctions 76 and ground. When, on the other hand, the switch 88 is closed and the switch 90 open, it will be seen that the condenser C13 is in parallel with the condensers C12 and that all of these condensers are in series with the condenser C14 between the terminal 76 and ground. In the latter case, the effectiveness of the condensers C12 in periodically changing the resonant frequency of any utilized networks 72 is less than when the switches 88 and 90 are in the first position. It is thus seen that the average capacity, looking into the network of condensers C12, C13, and C14 from the switch 77, is constant regardless of the positions of switches 88 and 90. This is musically desirable, and makes it easier for the player to select the tone control switches 74 necessary for obtaining a given or desired musical effect.

The over-all effect of periodically closing the switches 78 at about 7 C. P. S. is to cause the resonant frequency of either the first, second, or third voices or the resonant meshes 72 (or any combinations thereof which may be in use), to shift over a limited range, and thereby to produce a periodic tone quality change which may be perceived by the listener as a "quality vibrato." The effective operation of this apparatus depends upon the fact that the input signal is a complex wave rich in harmonics. (If the signal were a simple sine wave the effect would be substantially the same as that of amplitude modulation or a tremolo effect.)

From the foregoing it will be clear that in the quality vibrato the energy in a complex signal is periodically shifted from one band of frequencies to another, although the over-all energy level is maintained relatively constant. As a result, the musical tones heard by the listener do not have pronounced or even recognizable periodic changes in amplitude, but instead, the tones are perceived as having an indefinable richness associated with a vibrato, but, nevertheless, distinguishable from the vibrato through the fact that the tone quality instead of the pitch is varied.

Tone intensity envelope controls

The transformer T1 has its secondary provided with a center tap 92 and its end terminals connected to the grids 94, 95 of push-pull envelope determining tubes 96, 97. A center tap 92 on the secondary of transformer T1 is connected by an attack resistor R20 to a point of fixed potential, as +43 v. An attack condenser C16 is adapted, upon closure of an attack control switch 100, to be connected between the center tap 92 and the cathodes 102, 103 of the envelope determining tubes 96 and 97. The cathodes 102, 103 are normally maintained at a potential of +165 volts by virtue of their connection to a junction 104 of a voltage divider consisting of resistors R21 and R22. A large condenser C17 connects the junction 104 to ground to prevent rapid transient producing changes in potential at this point. The junction 104 is connected through a resistor R23 with a bus bar 106 with which the key switches 32 make contact. When any of the playing keys 30 is depressed, its switch 32 connects the bus

7
bar 106 to ground and thereby causes the potential at the junction 104 to shift from its static value of +165 volts to a value of +50 volts, thereby providing an operating grid bias of -7 volts on the tubes 96 and 97.

The attack circuit including the resistor R20, condenser C16, switch 100, voltage divider mesh of R21, R22 and R23, and C17 is similar to that shown in the aforesaid Patent No. 2,233,258 except that the resistance provided by the resistor R23 is, in said patent, provided by the windings of relays, and reference may therefore be had to this patent for the operation of this circuit.

The third key switches 33 are adapted to connect conductors 108 and 109 upon complete depression of the keys. The conductor 108 is normally connected to the screen grids 110 and 111 through a single-pole double-throw switch 112, while the conductor 109 is connected to a terminal 114 through a low value anti-spark resistor R26. The terminal 114 forms the junction of a relatively high impedance voltage divider mesh comprising resistors R24 and R25 connected between +300 v. and ground. Thus, upon depression of one of the keys sufficiently to operate its switch 33, an appropriate voltage (+150 v.) from the junction 114 is impressed upon the screen grids 110, 111 to render the tubes 96 and 97 conducting. The rate at which the operating voltage is applied to the screen grids 110, 111 may be selectively predetermined by operating any one or more of a plurality of switches 118, 119, 120 which selectively connect condensers C18, C19 and C20 between screens 110, 111 and ground. A resistor R27 is connected in parallel with the condenser C20.

In practice, condenser C18 is of relatively large value, such as 1 mfd., C19 is of lower value, such as .5 mfd., and C20 is made of still lower value such as 1 mfd., while R27 is relatively high, as 1 megohm. Thus, when any of the switches 33 is closed, the rate of increase of the potential on the screens 110, 111 will be determined by which of switches 118, 119, 120 or 121 is closed.

For example, assume that the switch 118 is closed. The rate at which the screen voltage is applied will then be controlled by the equal value resistances R24, R25 relative to the capacity of condenser C18. It will be noted that before any of the switches 33 is closed, the corresponding key switch 32 will have been closed, closure of which applies appropriate operating control grid bias on tubes 96, 97. Thus, when any of the key switches 33 is closed, the screen voltage applied thereby will cause plate current to flow in tubes 96, 97. It will be apparent that the increase in plate current is controlled by the operation of switches 33, and that the rate of increase in plate current is determined by the rate at which the screen voltage rises. If a more prompt attack is desired switch 118 may be left open and switch 119 closed. In this case, both the attack and decay will be of shorter duration because condenser C19 is smaller than condenser C18.

The voltage divider junction 114 may be connected to ground through a relatively large condenser C21 upon closure of a switch 122. Closure of switch 122 causes condenser C21 to serve as a voltage reservoir for imparting very prompt attack to the applied screen voltage when any of the switches 33 is closed. Closure of switch 122, however, does not influence the decay rate, which latter is entirely a function of the capacity of condensers C18, C19 and C20 serving as reservoirs of

screen voltage after the depressed key is released sufficiently to permit its switch 33 to open. The rate at which the screen voltage decreases after all of the switches 33 are open is determined by the rate at which the screen current discharges such of the condensers C18, C19 and C20 as may have their associated switches closed. Since the decrease in potential of the screens 110, 111 causes a corresponding decrease in plate current, the rate of decrease of screen grid potential is not linear, but becomes less and less rapid as the screen voltage decreases. Thus, the tone intensity envelope produced will be similar to that of a chime in that the decrease in amplitude will initially be at a relatively rapid rate and thereafter at progressively lower rates.

When it is desired to have the tones decay relatively rapidly, the switches 120 and 122 are closed. Under these circumstances the attack will be rapid due to the fact that the condenser C21 is in the circuit, but the tone will likewise decay rapidly both through the load of the tubes 96, 97 and also due to the load resistor R27 to ground. As the charge on condenser C20 becomes dissipated through screen current flow, the effect of R27 increases, serving further to reduce the screen potential (and resulting plate current) very much more rapidly to cut off potential, than if this resistor were not in the circuit.

In order to make it possible selectively to maintain the signal transmitted by the tubes 96, 97 at a relatively constant amplitude, there are provided a pair of resistors R28 and R29 which, upon closure of switches 123 and 124 respectively, connect the relatively constant potential junction 114 (150 volts) directly to the screen grids 110 and 111. The resistors R28 and R29 are of different values such as 3 megohms and 1 megohm, and are thus effective to drop the voltage on the screen grids to different values representing final or minimum amplitude levels of the plate current of tubes 96 and 97. For the values of the circuit elements mentioned above, it is assumed that the tubes 96 and 97 are remote cutoff pentodes of the 7A7 type.

As previously indicated, and as will hereinafter be described in greater detail, the switches 33 are operated by a so-called "second touch" of the playing keys 30, and it requires some training to acquire the proper technique for playing the instrument with this second touch. Means have therefore been provided selectively to eliminate the second touch feature, but nevertheless making it possible to obtain percussion tone intensity envelopes. The means for eliminating the effect of the second touch switches 33 comprises a switch 126 by which the conductors 108 and 109 may be connected.

With the switch 126 closed, the switch 112 may be swung to its dotted line position, thereby connecting the screen grids 110, 111 to the junction 114 of the voltage divider through a relatively high resistance R30 and connecting the screen grids to ground through a relatively large value condenser C22. When these switches are thus positioned (assuming that switch 100 is open) and no playing key is depressed, the voltage on the screen grids 110, 111 is maintained at +150 volts, which is the potential of the junction point 114. However, when a key is depressed and the control grid bias on the tubes 96, 97 changed to render these tubes conducting, the screen grids commence to draw current at the expense of the charge on the condenser C22. The resulting de-

crease in potential across the condenser C22 and the consequent decrease in plate current will continue until the current flow through the resistance R30 is sufficient to maintain the screen grids at a constant final potential. The musical effect of such setting of the switches 112 and 126 is that the tones produced have percussive banjo-like intensity envelope characteristics.

Playing key switches

In order to make it easy for the player to control the intensity envelope, the key switch 33 constitutes "a second touch switch" which is closed only when a pressure in excess of the normal pressure is exerted upon the key. A representative construction of this type is shown in Figure 3 wherein it will be noted that the key 30 is pivoted on a fulcrum 130, and is held in position by a stud 132 passing through an enlarged opening in the end of the key stem. A compression spring 134 is provided, the degree of compression of which may be adjusted by nuts 136 on the stud 132, which provides the force for returning the key to normal position. A suitable down stop and an up stop for the key, of the usual construction, are provided.

The key 30 has an insulating actuating portion 138 which engages the uppermost of a series of spring fingers 140, 141, 142, 143, 144, these switch arms being provided with suitable contacts as shown. Spring arms 140, 141 and 142 are relatively thin and flexible, while the spring arms 143 and 144 are less resilient so that upon depression of the key, the switches 31 and 32 will close in sequence, and the spring arm 143 will afford sufficient resistance to further depression of the key so that the switch 33 will thereafter be closed only when the player exerts a considerable additional pressure. It will be understood that any suitable second touch key operating system may be employed in place of that shown in Figure 3.

Volume control

The plates of the tubes 96, 97 are connected to the primary of an interstage transformer T2 and are supplied with operating potential through load resistors R30 and R31. The secondary of the interstage transformer T2 is connected to the grids 150 and 151 of volume control tubes 152, 153 which may also be of the remote cutoff type such as the 7A7. The suppressor grids and cathodes of these tubes 152 and 153 are connected to a terminal of fixed positive potential +50 v. The secondary of the transformer T2 has a center tap 154 which is connected to ground through a time constant condenser C23, and is adapted to have its potential controlled, to determine the amplitude of the signal transmitted by the pentodes 152, 153. The biasing potential is provided by a voltage divider comprising resistors R40 to R49 connected to the center tap 154 through a decoupling and time constant resistor R50. The resistor R42 is adjustable so as to determine the control grid bias corresponding to maximum volume.

A volume control contactor 156 is connected to ground, and is normally in contact with all of a plurality of switch contact elements 158, and operated by a lever 157 which may be moved by the knee, foot, or hand successively to break these contacts, commencing with the lowermost contact. The lever 157 may be spring returned against a stop 159 and is moved from its full line to its dotted line position to increase the volume.

It will be noted that when the contactor 156 is in its minimum volume position, the resistor R50 is directly connected to ground so that the grids 150, 151 have a biasing voltage which is effectively 50 volts negative with respect to the cathodes. For the particular tubes used, this is near cutoff and represents the minimum volume condition. Condenser C23 and resistor R50 render the volume increments smooth to prevent undesirably sudden changes in volume. The volume control tubes 152 and 153 have their outputs resistance-capacity coupled to a push-pull power amplifier comprising pentodes 160, 161, the output of which is transformer coupled to a speaker 162.

It is sometimes desirable to vary the resonance frequency of the tone control system incidental to changes in volume, to simulate the effect upon the listener of a symphony orchestra wherein as the general intensity level of the selection is decreased the tones of certain instruments seem, due partially to the room wall reflection characteristics, to decrease in volume irregularly with respect to the change in volume of the tones of other instruments. For this purpose the volume control lever carries a grounded contactor 163 normally (in minimum volume position) making contact with a plurality of contacts 164, and adapted successively to break the connection with the contacts 164 as the lever 157 is moved from minimum volume to full volume position. A plurality of condensers C12A, which correspond in function to the condensers C12, each has one terminal connected by one of a plurality of single-pole double-throw switches 165 to the contacts 164, and have their other terminals connected to a conductor 166 which is adapted, upon closure of a switch 168, to be connected to a conductor 169 to which one terminal of each of the condensers C12 is also connected. The total capacity of the condensers C12A should be equivalent to the total capacity of the condensers C12, although there may be more of the condensers C12A so that there may be small incremental changes in resonant frequency as the volume control lever 157 is operated.

The switching mechanism 163, 164 and the condensers C12A have the effect of changing the resonant frequency of the particular tone controls in use as the volume is changed. This general effect may be accomplished by other means since the condensers C12A or equivalent impedance elements may be connected in the output circuit in any suitable manner to change the tone quality of the transmitted signal or a portion thereof, as the over-all volume is changed. For example, upon changing the positions of the switches 165, by means of a manual control 167, resistors R51 may, in effect, be substituted for the condensers C12A, and under these circumstances, as the volume control lever 157 is moved from minimum volume position to maximum volume position, the quality of either the first, second or third voices taken singly or in combination (depending on which of the switches 74 is open and assuming, for maximum effectiveness, that switch 90 is closed and switch 88 is open), will slowly build up in sharpness of resonance along with the increased over-all volume. Thus, as the volume builds up the tone quality will smoothly change, and an orchestral crescendo will be simulated.

The changing resistance effected by successively disconnecting resistors R51 from the circuit as the volume is increased is intended as

representative of any suitable means, such as varying the grid bias on a control tube, whereby the quality of the transmitted signal, or a portion thereof, is changed in suitable relationship with changes in volume.

Modified tone intensity envelope controls

In some cases it may be desirable to utilize the instrument as part of an orchestra in which one player will devote his full attention to the playing of the instrument. Since the instrument is a solo instrument that requires but one hand for the manipulation of the playing keys, the player has the other hand free for the operation of the various controls. This makes it feasible to refine the tone intensity envelope controls so that more varied and interesting musical effects may be obtained by the player. The means for accomplishing this result is shown in Figure 2 which, it will be recalled, is to be substituted for the network between the lines *a-a* and *b-b* of Fig. 1b. In Figure 2, the interstage transformer *T*₁ has its secondary winding connected to control grids *170*, *172*, *174*, and *171*, *173*, *175* of parallel push-pull control tubes *176*, *178*, *180* and *177*, *179*, *181* respectively, which are preferably remote cutoff pentodes of the 7A7 type. The plates of the tubes *176* to *181* are connected in push-pull parallel to the primary winding of the interstage transformer *T*₂. The suppressor grids and cathodes of the tubes *176* to *181* are connected together to the terminal *104* of the voltage divider previously described.

The screens of the first set of the control tubes *176*, *177* are connected to a conductor *182* through an anti-spark resistor *R*₅₉ and are connected to ground through an envelope determining condenser *C*₂₆. In a similar manner the screen grids of pentodes *178*, *179* are connected to a conductor *184*, and are connected to ground through a condenser *C*₂₇. Likewise, the screen grids of the pentodes *180*, *181* are connected to a conductor *186* through an anti-spark resistor *R*₆₃, and are connected to ground through a condenser *C*₂₈, which latter is shunted by a resistor *R*₅₂.

A switch *188* is connected to the conductor *108* so as to disconnect the switches *33* from the circuits, and thus to render the second touch ineffective.

There are three keys *190*, *191* and *192* which may be played in conjunction with the depression of the playing keys *30*, thereby to determine which of the pairs of envelope controlling tubes *176*—*177*, *178*—*179*, or *180*—*181*, and their associated circuits shall be determinative of the envelopes of the tones. The keys *190*, *191* and *192* are spring-returned and may, in this respect, be similar to the keys as shown in Figure 3. These keys may be operated singly or in combination.

The envelope controlling tubes *176*, *177* are provided for producing an intensity envelope having a sharp attack and a relatively long decay time. The key *190* is adapted upon depression to close a switch *194* which connects the screen grids of the tubes *176*, *177* to a junction *196* of a voltage divider comprising resistors *R*₆₀ and *R*₆₁ connected between a +300 v. terminal of the power supply system and ground. The resistor *R*₆₁ is shunted by an attack controlling condenser *C*₃₀. Thus, upon depression of the key *190* (assuming that a signal is supplied to the interstage transformer *T*₁), a screen voltage of approximately 150 volts will be supplied to the screen grids of tubes *176*, *177*. This 150 volt potential represents full operating screen grid voltage, and as long as

switch *194* is closed, the plate currents of tubes *176* and *177* will be at their maximum values.

Assuming that one of the playing keys *30* remains depressed, release of key *190* will result in the relatively slow discharge of condenser *C*₃₀, which serves as a reservoir of screen voltage after said key has been released. As the voltage on condenser *C*₃₀ decreases, the screen current also decreases. The plate current therefore decreases and a tone intensity envelope is produced which has a smooth and musically pleasant decay rate. The condenser *C*₃₀ serves as a screen potential reservoir so that when the switch *194* is closed, the full screen potential will substantially immediately be impressed upon the screens of the tubes *176*, *177*, thereby causing a percussive or rapid attack.

The junction *196* of the voltage divider is adapted to be connected to the conductor *182* through resistors *R*₆₂, *R*₆₃ upon closure of switches *197*, *198* respectively, these resistors being of different values and serving to maintain a potential upon the screen grids of the tubes *176*, *177* for an indefinite period after the switch *194* has been opened, thereby to determine a final intensity level beyond which the tones will no longer decay. It will be noted that in effect the switch *194* has the same functions as the second touch switches *33*.

The intensity control tubes *178*, *179* are provided for obtaining a slow attack and a very long decay. The conductor *184* for these tubes is adapted to be connected by depression of the key *191*, and consequent closure of a switch *200*, to a junction point *202* of a voltage divider comprising resistors *R*₆₄ and *R*₆₅ connected between +300 v. terminal of the power supply system and ground. Thus, upon closure of the switch *200*, an operating potential of approximately 150 volts is impressed upon the screen grids of the tubes *178*, *179* at a rate determined by the condenser *C*₂₇ and the values of resistors *R*₆₄, *R*₆₅. The full operating potential will thereafter be maintained upon these screen grids as long as the key *191* is held depressed, and upon release of this key the potential will decrease at a very slow rate, to produce a tone intensity envelope simulating that of a chime, as the condenser *C*₂₇ is discharged.

The envelope control tubes *180*, *181* are for the purpose of obtaining a rapid attack and rapid decay, and are under the control of the key *192* which, when depressed, successively closes switches *204*, *205* and *206*. Closure of the switch *204* connects the conductor *182* to ground through a rapid decay resistor *R*₆₆, while closure of switch *205* similarly connects the conductor *184* to ground through a rapid decay resistor *R*₆₇. Closure of the switch *206* connects the conductor *186* to the junction terminal *196* of the voltage divider comprising resistors *R*₆₀ and *R*₆₁.

The closure of the switches *204* and *205* causes the signal transmitted by the tubes *176*, *177*, *178* and *179* to decay very rapidly so that when the switch *206* is closed, the signal may rapidly build up, and when the switch *206* is opened, will rapidly decay to silence (and will not be transmitted by tubes *176*, *177*, *178* and *179*). If the switches *204* and *205* were not provided, this rapid decay to silence could not occur if the player had just previously depressed keys *190* or *191*. Such operation of key *190* or key *191* would produce a long decay envelope which might interfere with the effective operation of the key *192*.

Resistor *R*₅₂ functions in a manner to cause rapid decay of the screen potential (correspond-

ingly the plate current of tubes 180, 181 in a manner previously described with respect to condenser C20 and resistor R27 (Fig. 1b).

Operation

The operation of the various portions of the instrument have been described, and it will therefore be necessary merely to summarize the operation of the instrument as a whole.

Assuming that the instrument comprises the circuits of Figs. 1, 1a and 1b, the musician will play it in the manner of a melody instrument—that is, only one key at a time. In making use of the second touch feature provided by switches 33, the musician will usually play in a smooth legato manner insofar as the operation of the contact switches 131 and 132 is concerned, and will apply additional key pressure for the operation of the switches 33 only at times when a musical accent is desired, or at other times when the percussive envelope provided by the second touch is desired. The musician will find that by playing in a legato manner, very effective glissandos and slurs between notes may be played at low levels (that is, without the use of the second touch), whereas the termination notes of these glissandos and slurs, which are the notes actually scored, will be made relatively prominent by applying further finger pressure to operate the second touch switches and thus impart musical accents to the tones produced. This type of glissando and slur is very interesting musically because the melody notes of the musical selection being rendered stand out from the less important, but nevertheless musically pleasant, incidental, glissando, or passing notes.

Another important effect achieved through the use of the second touch feature resides in the fact that the tones produced are devoid of any "dead room" effect, which would be unavoidably present in this type of sustained tone melody instrument in which a single oscillator is employed. Of necessity the decay portion of the envelope associated with the switch 32 must be very rapid so as substantially to cut off the amplifier portion of the instrument in a time comparable to the key release time. In practice, this allowable time is very short (in the order of 20 milliseconds), and affords time sufficient only for elimination of electrical transients such as clicks and thumps. The second touch switches 33 and circuits controlled thereby make it possible to produce intensity envelopes having a decay period as long as two or three seconds, so that the musically desirable reverberatory effect of a large auditorium may be obtained. In addition, by making the decay rate somewhat shorter, the effect of percussion instruments may be obtained.

In practice, the playing technique is relatively easy for the musician to achieve, since he need merely use a continuous legato style with the important and accented tones being emphasized by operating the second touch switch.

When the instrument is constructed to incorporate the circuits of Fig. 2, the previously described technique of playing becomes still more versatile as the right hand is used substantially solely for determining the pitch of the tones, and the left hand is free successively to impart one or a plurality of envelopes of varying attack and decay characteristics. This makes it possible to put added vigor and life into the expression of the music being rendered as, for instance, by imparting sharp attack and decay envelopes on accented notes, and smooth attack and decay

envelopes on notes which are played in less strict time, as in rubato passages. By having individual spring returned keys for controlling the envelopes, it is easily possible to change the character of the tone envelopes in succession in exact accordance with the change of expression desired in successive musical notes of the melody.

It will be noted that it is not necessary to maintain the second touch switch 33 closed throughout the time it is desired that the tone shall be sounded. The tone may be made to decay at a desired rate following the opening of the second touch switch 33. Similarly, in the embodiment shown in Fig. 2, the tone will continue to sound at a predetermined decay rate after the envelope determining key or keys (190, 191, 192) have been released. Furthermore, repetition of a single tone may be accomplished by holding the playing key depressed while repeatedly depressing one or more of the envelope determining keys.

The quality vibrato mechanism provided by the switches 78 and associated circuits and mechanism is of general utility and may be used with any type of musical instrument producing signals of high harmonic development.

While I have shown and described particular embodiments of my invention, it will be apparent to those skilled in the art that numerous variations and alterations may be made in the circuits and apparatus without departing from the underlying principles of the invention. I therefore desire, by the following claims, to include within the scope of my invention all such modifications and variations whereby substantially the results of my invention may be obtained by the use of substantially the same or equivalent means.

I claim:

1. In an electrical musical instrument having an electrical musical tone signal generating system and an output system including an electro-acoustic translating means, the combination of a signal transmission system coupling said generating system to said output system, a pair of pentodes connected in push-pull and forming a part of said signal transmission system, means for impressing the signals from said generating system across the grids and cathodes of said pentodes, means normally biasing the control grids of said pentodes beyond cutoff, a plurality of playing keys, means operated by said playing keys upon initial depression thereof for changing the grid bias on said pentodes to a value rendering said pentodes capable of transmitting the signal, a source of operating potential for the screen grids of said pentodes, and means connecting said source to the screen grids of said pentodes upon complete depression of any of said keys.
2. The combination set forth in claim 1 in which said source is of relatively high impedance and a condenser is connected between said source and a point of fixed direct current potential to serve as a voltage reservoir at said source.
3. The combination set forth in claim 1 in which said source is of relatively high impedance, and there is provided a plurality of condensers of different values selectively connected between the screen grids of said pentodes and a point of fixed potential to provide a gradually decreasing operating potential for the screen grids after disconnection of said source from the screen grids upon key release.
4. The combination set forth in claim 1 in which a plurality of resistors of different relatively high

value are selectively connectable between said source and the screen grids of said pentodes to maintain the screen grids at predetermined potentials within the operating potential range thereof.

5. The combination set forth in claim 1 in which said source is of relatively high impedance and there is provided a condenser selectively connectable between the screen grids of said pentodes and a point of fixed potential to provide a gradually decreasing operating potential source for the screen grids after they have been disconnected from said source.

6. The combination set forth in claim 1 in which a relatively high impedance is selectively connected between said source and the screen grids to provide a path for maintaining an operating potential on the screen grids after the key controlled connection between said source and screen grids has been broken by the release of the depressed key.

7. In an electrical musical instrument having an electrical musical tone signal generating system and an output system including an electro-acoustic translating means, the combination of a signal transmission system coupling said generating system to said output system, a plurality of playing keys, a plurality of tone intensity envelope determining keys, a plurality of pairs of pentodes connected in push-pull and forming parallel signal transmission paths, a source of screen potential, and a plurality of resistance-capacity meshes respectively connected upon operation of said envelope keys between said source and the screen grids of pairs of said pentodes.

8. The combination set forth in claim 7 in which one of said envelope keys controls the connection in sequence of at least two of said meshes to the screen grids of two pairs of said pentodes.

9. In an electrical musical instrument of the melody type having a key-controlled electrical tone frequency generating system and an output system including electroacoustic translating means, the combination of a signal transmission system coupled between the generating system and the output system, said signal transmission system including a pair of multi-electrode electron discharge devices connected in series, and a resistance mesh in the input circuit of each of said devices to limit the grid current thereof during the positive half cycle of its input signal sufficiently to cause the production of an output signal from the second of said devices in which the even harmonics are appreciably attenuated.

10. In an electrical musical instrument having a variable frequency generator and a plurality of playing keys operable to control the frequency of operation of said generator and an output system including electroacoustic translating means; the combination of transmission means for conducting signals from said generator to said output system, said transmission means including a pair of electron discharge devices connected in series, each of said devices having a control grid and circuit elements connected to said devices to cause the latter to distort a sine wave input signal to a wave shape representing the fundamental frequency of a sine wave input and a pronounced odd harmonic series, said circuit elements including current limiting resistors respectively connected in series with said control grids.

11. A signal transmission system for coupling the tone frequency generating system of an electrical musical instrument to its output system, the latter including electroacoustic translating

means; said transmission system comprising two cathode-grid-plate electron discharge devices in series, each of said devices comprising resistance means forming the sole connections between their respective grids and cathodes, said resistance means operating to limit the extent of positive swing of the grid by forming a path for the flow of grid current, and means coupling said devices in series.

10. 12. In an electrical musical instrument the combination of a variable frequency electrical generator, a plurality of playing keys, three switches associated with each of said keys and sequentially operated thereby, a signal transmission system, means controlled by the first-operated switch to determine the frequency of operation of said generator, means controlled by the second-operated switch to condition said transmission system for operation, and means, including a resistance-capacitance mesh in said signal transmission system, controlled by said third-operated switch to determine the amplitude envelope of the signal transmitted by said transmission system.

15. 13. The combination set forth in claim 12 in which mechanical means are provided to necessitate the operation of said keys with increased pressure in order to secure operation of said third-operated switch.

20. 14. In an electrical musical instrument having a signal generating system, an output system including an electron discharge device provided with a cathode, control grid, anode and second grid, manually operable keys for selectively controlling the transmission of musical signals from said generating system to the control grid and cathode of said device, means controlled by said keys to determine the grid bias on said device, and additional means controlled by said keys near the ends of their strokes to vary the potential on said second grid, said last named means including a resistance and capacitance mesh connected to said second grid upon the complete depression of any one of said keys.

25. 15. The combination set forth in claim 14 in which said mesh includes circuits selectively rendered effective to prevent the potential of said second grid from dropping below a predetermined value.

30. 16. The combination set forth in claim 14 in which said mesh includes a plurality of condensers and selectively operable means for connecting said condensers between said second grid and a point of fixed direct current potential thereby to determine the rate at which the potential of said second grid may change from a value at which said electron discharge device is rendered conductive to a higher value.

35. 17. The combination set forth in claim 14 in which said mesh includes a condenser connected to said second grid, and a high resistance path for charging said condenser and maintaining said second grid at a potential at which said device is conductive.

40. 18. In an electrical musical instrument, the combination of an electrical variable musical frequency signal generating system, playing keys, means controlled by the partial depression of said keys for determining the pitch of the musical note frequencies provided by said generating system, a signal transmission system connected to said generating system, said transmission system including an electron discharge device normally non-conductive of said signal, means controlled by the partial depression of said keys to render

said device conductive of said signal, a second electron discharge device in series with said first electron discharge device for controlling the tone intensity envelope of the signal transmitted thereby, and means operated by the complete depression of any one of said keys to change the operating potentials on said last named electron discharge device to cause the production of a tone having a percussive envelope.

19. In an electrical musical instrument having electrical signal generating means, an output system, and playing keys controlling the transmission of signals from the generating means to the output system; an electron discharge device forming part of said output system for transmitting the signal produced by the generating means, said device having a cathode, anode, control grid and a second grid, a source of operating potential for said second grid, a resistance-capacitance network, and manually operable key means for selectively connecting said second grid to said source through a predetermined portion of said network thereby to determine the character of amplitude envelope of the signal transmitted by said device.

20. In an electrical musical instrument having electrical tone signal producing means and having an output system including electroacoustic translating means, a signal transmission circuit including a multi-electrode electron discharge device having a screen grid, a condenser connecting said screen grid to a terminal of fixed direct current potential, a potential source of value substantially equaling the normal operating potential of said screen grid, and a manually operable switch for connecting said screen grid to said source.

21. The combination set forth in claim 20 in which a relatively large energy storing condenser is connected between said source and a point of fixed direct current potential of value differing materially from that of said source.

22. In an electrical musical instrument having a plurality of variable frequency generators interlocked for operation at octave interval frequencies, a plurality of playing keys, means controlled by said keys for causing said generators to operate at frequencies of the notes of the musical scale, an output circuit for said generators, said output circuit including an electron discharge device having a cathode, control grid, anode and a second grid, means for impressing signals from said generators between said control grid and cathode, a circuit completed upon the depression of any one of said keys to change the grid bias on said electron discharge device to a value at which said device may transmit the signal, a third switch under each of said keys, said third switches being connected in parallel, and a resistance and capacitance network connected with said third switches and operable to vary the potential upon said second grid thereby to control the intensity envelope of the signal transmitted by said device.

23. Means for altering the tone quality of a musical signal to accentuate the odd harmonics thereof comprising, a first electron discharge device having a cathode, control grid, and anode, an output circuit therefor, a second electron discharge device having a cathode, control grid, and anode, a signal input circuit for said first device including biasing means limiting the positive amplitude of the impressed signal to a predetermined value whereby the positive portion of the input signal wave is distorted to have a

generally rectangular shape, and means coupling the output circuit of said first device to the input of said second device including biasing means limiting the positive amplitude of the signal to cause it to have a generally rectangular shape, whereby the output signal of said second device will have a wave form representative of a fundamental frequency and predominant odd harmonics thereof.

24. In an electrical musical instrument having playing keys and having a signal transmission output circuit including an electron discharge device having a cathode, control grid, anode and a second grid; a resistance-capacity network connected between the source of potential and said second grid rendered effective upon depression of said playing keys to vary the potential on said second grid in a preselected potential-time pattern to cause the signal to be transmitted by said device to have a tone intensity envelope corresponding to said potential-time pattern, and manually operable switches in said network for changing the potential-time pattern on said second grid which is produced when a playing key is depressed.

25. In an electrical musical instrument having an electrical musical signal generating system, an output system including electroacoustic translating means, and a signal transmission system coupling the generating system with the output system, the combination of a plurality of manually operable keys, at least two switches sequentially operable by each of said keys when said key is fully depressed, means associated with each of said keys to impart noticeably increased resistance to depression of the key after it has operated the first switch and prior to its operation of the second of said switches, and means in said transmission system responsive to the operation of said switches to determine the shape of the intensity envelope of the signal produced by said generating system and transmitted to said output system.

26. In an electrical musical instrument having an electrical musical signal generating system, an output system including electroacoustic translating means, and a signal transmission system coupling the generating system with the output system, the combination of a manually operable key capable of movement in addition to its normal movement, two electrical control means associated with said signal transmission system and effective to determine the intensity envelope of the transmitted signal, means associated with said key for rendering said two electrical control means sequentially effective, the first of said electrical control means being rendered effective upon normal operation of said key, and the second of said electrical control means being rendered effective by movement of said key in addition to its normal movement.

27. In an electrical musical instrument having an electrical musical signal generating system, an output system including electroacoustic translating means and the signal transmission system coupling the generating system with the output system, the combination of a plurality of manually operable keys, at least two switches sequentially operable by each of said keys, means to operate the first of said switches by operation of its associated key in a normal manner, means to operate the second of said switches by operation of said key to produce movement thereof in addition to its normal movement, and means in said transmission system responsive to the

operation of said switches to determine the intensity envelope of the signal produced by said generating system and transmitted to said output system.

28. In an electrical musical instrument having electrical musical tone signal producing means and having an output system including electro-acoustic translating means, a circuit for transmitting an electrical signal from said signal producing means to said output system, said circuit including a multi-electrode electron discharge device, a pair of the electrodes thereof forming input electrodes connected to receive a signal from said signal producing means, another pair of the electrodes thereof forming output electrodes connected to transmit a signal to said output system, and one of the electrodes thereof being of a character such that the direct current potential impressed thereon determines the gain of said device, tone intensity envelope control keys, sources of relatively fixed direct current potential, a plurality of resistance-capacitance meshes, and switches operated by said keys for selectively connecting said meshes between said sources and said gain controlling electrode.

29. In an electrical musical instrument having a plurality of playing keys, an electrical musical tone signal generating system, an output system including electroacoustic translating means and a signal transmission system coupling said generating system to said output system, the combination of a variable gain means in said signal transmission system, second touch means operated by the playing keys when they are depressed more than a predetermined extent and including means for imparting an increased resistance to depression of the keys as they are moved beyond the predetermined extent, and a connection between said second touch means and said variable gain means to cause the latter to effect an increase in the gain of said signal transmission circuit when any one of said keys is depressed substantially beyond said predetermined extent.

30. In an electrical musical instrument having a plurality of playing keys comprising a keyboard extending throughout at least a two octave range, a master oscillator tunable throughout a frequency range equalling that of the keyboard range, a series of cascaded frequency dividing stages having their frequencies of operation stabilized by said master oscillator and each operating at a frequency one half that of the preceding stage, means controlled by operation of said keys to tune said master oscillator to a frequency corresponding to that of a depressed key and thereby to cause said frequency dividing stages to operate at frequencies successively one octave lower than that of the master oscillator, and means to selectively utilize signals from said frequency dividing stages and from said master oscillator.

31. In an electrical musical instrument having pitch determining playing keys, an electrical musical signal generating system, and a signal transmission system, playing keys to control the transmission of tone signals from the generating system to the transmission system, said transmission system comprising variable gain means effective to control the intensity envelope of the transmitted signal, and a plurality of control keys independent of said playing keys and operable upon depression to selectively determine the rate of increase of gain of said transmission system thereby to determine the rate and extent of at-

tack portion of the tone intensity envelope, and means associated with said variable gain means and operated upon release of the playing key to cause the gain to decrease at a controlled rate and thereby automatically produce the decay portion of the tone intensity envelope.

32. In an electrical musical instrument having an electrical tone signal generating system and a signal transmission system including electro-acoustic translating means, the combination of a plurality of pitch controlling playing keys, a plurality of manually operable tone amplitude control elements, means controlled by said playing keys to cause tone signals from the generating system to be supplied to the transmission system, and means in the transmission system including resistance-capacitance potential controlling circuits rendered operable by said control elements for controlling the intensity envelopes of the tone signals transmitted.

33. In an electrical musical instrument having an electrical tone signal generating system and a signal transmission system including electro-acoustic translating means, the combination of a plurality of playing keys for determining the pitch of the tone signals supplied to the transmission system, a plurality of manually operable tone intensity envelope control elements, means controlled by said playing keys to cause tone signals from the generating system to be supplied to the transmission system, and a plurality of resistance-capacitance potential controlling circuits in the transmission system selectively rendered effective by said control elements to control the intensity envelopes of the tone signals transmitted.

34. In an electrical musical instrument the combination of means for generating electrical signals representing musical tones, a signal transmission system, a plurality of playing keys operable to determine the pitch of the tone signals supplied by said generating system to said transmission system, means including resistance-capacitance potential controlling circuits and forming part of said transmission system for controlling the intensity envelopes of the signals transmitted by said transmission system, and a plurality of manually operable keys for controlling said last named means.

35. In an electrical musical instrument having a generator capable of producing electrical signals corresponding to musical tones, a signal transmission system including electroacoustic translating means, a plurality of playing keys for determining the pitch of the tone signal supplied by the generator to the transmission system, signal amplitude controlling means associated with said transmission system including a plurality of electrical resistance-capacitance potential controlling networks for determining tone intensity envelopes, and a plurality of manually operable controls for selectively rendering one or more of said networks effective.

36. In an electrical musical instrument having electrical signal generating means, signal transmission means, and means for translating the electrical signals into sound; said signal transmission means comprising a plurality of electron discharge devices, each having a control grid, screen grid, cathode, and anode; means for impressing the musical signal on the control grids of all of said devices; a plurality of playing keys; circuits controllable by said playing keys to determine the grid bias on all of said devices; an output circuit connected to said anodes in paral-

iel; a plurality of resistance-capacitance meshes, one associated with the screen grid of each of said devices; a source of screen grid operating potential connected to said resistance-capacitance meshes; and a plurality of selectively operable controls for coupling said resistance-capacitance meshes to their associated screen grids, respectively, thereby to apply operating potentials to said screen grids at selectively predetermined rates.

37. In an electrical musical instrument which requires playing by both the player's hands, the combination of a signal transmission circuit, pitch determining keys playable by one hand, tone intensity envelope determining keys playable by the player's other hand, a plurality of attack and decay circuits controlled by said envelope determining keys to smoothly make operative the signal transmission circuit, each of said attack and decay circuits including means to produce a predetermined smooth attack when its asso-

ciated key is depressed and including a potential storage element operative to prolong the decay portion of the envelope independently of the playing keys.
